UNITED STATES PATENT OFFICE.

SAMUEL MERRETT STEVENS, OF ASHEVILLE, NORTH CAROLINA.

COMBINED PAPER-WEIGHT AND PENCIL-SHARPENER.

1,207,810.

Specification of Letters Patent. Patented Dec. 12, 1916.

Application filed January 9, 1915. Serial No. 1,380.

To all whom it may concern:

Be it known that I, SAMUEL M. STEVENS, a citizen of the United States, and a resident of Asheville, in the county of Buncombe and State of North Carolina, have invented a new and Improved Combined Paper-Weight and Pencil-Sharpener, of which the following is a full, clear, and exact description.

10 My invention relates to a paper weight having a novel handle equipped with pencil sharpener elements, so that the handle serves a two-fold function.

The invention is particularly adapted for 15 use as an advertising device, in which the paper weight presents panels available for advertising matter. In carrying out the invention also the top of the paper weight is made to constitute a receptacle for the 20 parings produced by the pencil sharpener.

The invention will be particularly explained in the specific description following.

Reference is had to the accompanying 25 drawings forming part of this specification, in which similar characters of reference indicate corresponding parts in all the views, and in which:

Figure 1 is a perspective view of a paper weight embodying my invention; and Fig. 2 30 is a longitudinal vertical section.

In constructing a practical embodiment 35 of my invention in accordance with the illustrated example, the body 10 of the paper weight is made preferably oblong and of solid formation sufficient to serve the purpose of a paper weight, the opposite sides and ends of the paper weight presenting plain panels on which the advertising matter (not shown) may be displayed.

40 The paper weight is equipped with a handle 11 which is disposed longitudinally and supported above the body 10 of the paper weight by standards 12 integral with the body. The handle 11 is tubular and preferably of metal, and it may be supported by molding the opposite ends of the standards 45 12 in depressions 13 in the opposite faces of said standards. The standards 12 have counterbores 14 extending therethrough in alinement with each other and in alinement with the bore of the tubular handle 11, so that a pencil A to be sharpened 50 may be inserted into the handle from either end. Fitted in the ends of the tubular handle and in the counter-bores 14 are the tubular bodies 15 of pencil sharpeners, there be-

ing one pencil sharpener at each end of the handle 11. The pencil sharpeners may be of approved form; they are shown as having lateral wings 15^a and blades 17 arranged at 60 lateral slots 16. The tubular pencil sharpeners 15 extend beyond the ends of the handle into the counter-bores 14 and thereby constitute a strengthening element in the connection between the handle 11 and the 65 standards 12, which is an important feature in the case of glass standards.

In operation a pencil A is entered longitudinally in a pencil sharpener 15, and upon being turned and advanced in a well known 70 manner, the chips will escape laterally through the slots 16. The top of the body 10 of the paper weight is depressed at 10^a and is broader than the handle 11, so that the chips will be received in the said de- 75 pressed top.

To give completeness to the paper weight as a useful desk device, I provide in practice rack elements 18 consisting of lateral arms projecting at the front and back from 80 the standards 12. The outer ends of the arms 18 are up-turned so that two arms at the front or back will form a rack for the pencil, as indicated at B (Fig. 1).

In order to provide for the fitting of the 85 pencil sharpener in the tubular handle, the latter is formed with an elongated opening 11^a at the underside through which the pencil sharpener may be entered to be then moved endwise toward the ends of the tubu- 90 lar handle.

Having thus described my invention, what I claim as new and desire to secure by Letters Patent, is:

1. An article of the character described 95 comprising a body, standards on the body at the top and formed with lateral depressions in their inner faces and with counter-bores extending through the standards, a tubular handle extending at its ends into 100 said depressions above the body, the counter-bores of the standards alining with the interior of the handle, and pencil sharpeners fitted in the tubular handle at the ends and projecting beyond the same into the 105 said counter-bores, the tubular bodies of the sharpeners being open at the outer ends for the entrance of a pencil thereinto through the said counter-bores of the standards.

2. An article of the character described, 110 comprising a body, a tubular handle supported on the body above the top thereof

and formed with an elongated opening at the under side extending laterally into the handle to the hollow interior thereof, said opening terminating at its outer end short of the adjacent standard, and a pencil sharpener having a tubular body, the tubular body fitting in the tubular handle and having a cutter projecting through said opening, the outer end of said tubular body 10 of the sharpener extending beyond the said lateral opening, and being movable endwise

to bring its said extending end to the opening for removing the sharpener, and the outer end of the tubular body being open for the entrance of a pencil.

In testimony whereof I have signed my name to this specification in the presence of two subscribing witnesses.

SAMUEL MERRETT STEVENS.
